United States Patent Office

Des. 210,263

Patented Feb. 20, 1968

210,263

ATTACHÉ CASE

George Rapoport, 8417 Fountain Ave.,
Los Angeles, Calif. 90069

Filed Aug. 1, 1966, Ser. No. 3,281

Term of patent 14 years

(Cl. D87—5)

FIG. 1 is a perspective view of an attaché case showing my new design;

FIG. 2 is an end elevational view thereof as seen from the left of FIG. 1;

FIG. 3 is a top plan view; and

FIG. 4 is a bottom plan view thereof. The side of the case not visible in FIG. 1 is conventionally plain.

I claim:

The ornamental design for an attaché case, as shown and described.
